ADJUSTABLE LAMP SUPPORT

Arthur A. Karcher, Fostoria, Ohio

Application July 14, 1933, Serial No. 680,443

7 Claims. (Cl. 287—12)

This invention relates to lamp supports, and more especially to movable or articulated supports for an electric lamp bulb.

Generally stated, the object of the invention is to provide a novel and improved construction whereby a support of this kind has a plurality of ball and socket joints of novel formation, permitting the lamp to be placed in various positions, practically any position within the length of the support, and held in such position by tension in the ball and socket joints.

It is also an object to provide certain details and features of construction tending to increase the efficiency and desirability of a lamp support of this particular character.

To the foregoing and other useful ends, the invention consists in matters hereinafter set forth and claimed, and shown in the accompanying drawing, in which—

Fig. 1 is a plan view of a lamp support embodying the principles of the invention.

Fig. 2 is a side elevation of said lamp support.

Fig. 3 is one of the ball and socket joints taken apart.

As thus illustrated, the invention comprises a ball 1 rigid with a bracket 2, which latter may be fastened to the wall or any other support. The socket jaws 3 and 4 embrace said ball, and the jaw 4 is fastened to the tube 5, but the jaw 3 is not. A screw 6 is inserted through the two jaws, at a point between the ball 1 and the end of said tube, to tension the jaws on the ball.

A ball 7 is rigid with the other end of said tube 5, and the tube 8 is rigid with the jaw 9, but the jaw 10 is loose and connected to the jaw 9 by a screw 11, thereby to tension these jaws on the ball 7 between them. As shown more clearly in Fig. 3, the jaws 9 and 10 are formed with lugs 29 and 29 to engage the neck 12 of said ball, to limit relative motion of the tubes 5 and 8 in one direction, but permitting said tubes to swing toward each other in the opposite direction.

A socket jaw 13 is rigid with the other end of the tube 8, but the jaw 14 is loose and simply connected to the jaw 13 by the screw 15, to tension these jaws on the ball 16 between them. This ball is rigid with the angle neck 17, which latter is at an angle when the lamp is in axial alignment with the bracket arm, and is in turn rigid with the upper clamp 18 between which and the lower clamp 19 the lamp bulb 20 is clamped. The formation of the neck, as shown, permits a larger radius of location or action, as between the lamp and the tube 8, when it is desired to

adjust the lamp in some particular position. The two clamps are separably connected together by screws 21, and the shade 22 is preferably rigid with the upper clamp 18, to cover the upper side of the lamp bulb. The lower clamp 19 has a hook-like portion 23, and a wire guard 24 is hinged in the portion 23 and formed at its other end with portions for engaging the holes 25 in the shade. The thumb piece 26 of the lamp bulb extends upwardly through the slot 27 in the upper clamp.

The ball 7 is preferably smaller than the ball 1, and the ball 16 is preferably smaller than the ball 7, while the tube 8 is preferably smaller than the tube 5, whereby in effect the supporting arm 15 thus formed is tapered toward the lamp.

With this construction, the lamp can be turned or placed in practically any position within the length of the articulated arm thus formed, and the tension in the ball and socket joints maintains the lamp in the desired position.

The conductor cord 28 extends into the tube 5 and through the ball 7 into the tube 8, and then outside the ball 16 to the base of the lamp bulb. The adjustable lamp support thus formed may be mounted on the wall or on a bench, or on any object, and it may be fastened to a floor support to make it portable, if so desired. Each joint, obviously, has more movement in some directions than in others, because of the split or sectional formation of the sockets of the joints.

It will be seen that the sections 4, 9, and 13 of the ball and socket joints are fastened to the tubes by rivets 30, so that these sections are rigid with the tubes. These rivets are inserted and are secured to the tubes by spot welding, and in addition each rivet is thus welded to the section containing the hole in which it is inserted. It will also be seen, as shown in Fig. 3 of the drawing, that each ball and socket joint has a ball 40 socket formed by the sections 9 and 10, for example, as previously explained, and that the section 9 has a portion 31 that embraces the tube 8, and that the section 10 has a similar portion 32 that embraces the other side of the tube, when the screw 11 is inserted through the hole 33 and caused to engage the screw-threaded hole 34 at the opposite side.

With the foregoing construction, it will be seen that the electrical conductor 28 extends through all of the tubes, 5 and 8, and through all of the ball sockets, and through at least one of the balls of said ball and socket joints, whereby this conductor is practically entirely concealed within the jointed or articulated arm or bracket thus formed.

As the screw 11 is threaded in the loose jaw 18, and loose in the fixed jaw 9, it follows that the head of the screw is held in fixed position during any tightening or loosening of the jaws, making it easy to hold the jaw 18 in one hand, while the screw is being manipulated by the other hand, in connecting the two jaws together, so that finally a screw driver can be used with one hand, the head of the screw and the screw itself being held in fixed position against any wobbling relatively to the jaw 9 of the tube 8, during the general operation of connecting the two jaws together.

The relative formation of the clamping jaws 9 and 18, it will be seen, is such that the relative rotation between the ball 7 and its ball socket is limited to movement about a single axis, as the ball cannot rotate in any direction, but can only rotate in the direction afforded by the guiding edges of the jaws below the lugs 28, as these edges engage the neck 12 of the ball, and hold the latter against rotation in any other direction relatively to the ball socket. The same is true of the ball 1 and its ball socket, and the same is true of the ball 16 and its allotted ball socket, for in each case the neck of the ball can move in a guide slot, so to speak, formed between the edges of the clamping jaws, but cannot move relatively in any other direction.

What I claim as my invention is:

1. In a lamp arm, a ball and socket joint therefor comprising a tube with a ball on the end thereof, another tube with a pair of clamping jaws on the end thereof, forming a ball socket between them, and providing an articulated conduit for an electrical connection for the lamp, one jaw being rigidly fastened to the tube, the other jaw being loose on the opposite side of the tube, so that this other jaw has a clamping action at both ends thereof, a ball clamping action at one end and a tube clamping action at the other end, and a screw extending through the two jaws, between the ball and the second mentioned tube, said screw being loose in one jaw and screw threaded in the other jaw.

2. A structure as specified in claim 1, the outer ends of the jaws having lugs forming a stop to engage the neck of the ball, when said tubes are in straight alignment, to limit the turning movement of the ball in one direction, and the jaws forming a guide slot for said neck in the opposite direction.

3. A structure as specified in claim 1, both jaws having longitudinal channels fitting the sides of the second mentioned tube.

4. In a lamp arm, a ball and socket joint therefor comprising a member with a ball on the end thereof, another member with a pair of clamping jaws on the opposite sides of the end thereof, forming a ball socket between them, for said ball, and providing an articulated support for the lamp, one jaw being rigidly fastened to the member, the other jaw being loose on the opposite side of the member, so that this other jaw has a clamping action at both ends thereof, a ball clamping action at one end and a member clamping action at the other end, and a screw extending through the two jaws, between the ball and the second mentioned member, said screw being loose in one jaw and screw threaded in the other jaw, whereby relatively adjustable clamping jaws are provided, with the second mentioned member clamped between the jaws at one end of the latter, and with said ball clamped between them at the other end.

5. A structure as specified in claim 4, said members being tubular, and said ball having a bore, whereby the structure provides an articulated conduit for an electrical connection for the lamp.

6. A structure as specified in claim 4, said jaws being both provided on their inner faces with grooves in which the second mentioned member is clamped.

7. A structure as specified in claim 4, said jaws being formed relatively to the ball to limit the relative rotation between the ball and the ball socket to a single axis.

ARTHUR A. KARCHER.
